UNITED STATES PATENT OFFICE

PHILIP BERGH, OF PORTLAND, OREGON, ASSIGNOR TO JANTZEN KNITTING MILLS, OF PORTLAND, OREGON

DESIGN FOR A SWIMMING TRUNK

Application filed August 12, 1929. Serial No. 32,397. Term of patent 14 years.

To all whom it may concern:

Be it known that I, PHILIP BERGH, a citizen of the United States, residing at Portland, in the county of Multnomah, and State of Oregon, have invented a new, original, and ornamental Design for Swimming Trunks, of which the following is a specification, reference being had to the accompanying drawing forming a part thereof.

In the drawing—

Fig. 1 is a side view of a swimming trunk embodying my new design, the shading thereon indicating contrasting colors; and

Fig. 2 is an edge view thereof.

I claim:

The ornamental design for a swimming trunk, as shown and described.

PHILIP BERGH.
